(57) **CLAIM**

The ornamental design for a flexible bulk garden product bag, as shown and described.

DESCRIPTION

FIG. 1 is a top front left perspective view of a flexible bulk garden product bag embodying our design;

FIG. 2 is a front elevational view of the flexible bulk garden product bag of FIG. 1;

FIG. 3 is a cross-sectional view of the flexible bulk garden product bag, taken along lines 3-3 of FIG. 2;

FIG. 4 is a left side elevational view of the flexible bulk garden product bag of FIG. 1;

FIG. 5 is a left side elevational view of the flexible bulk garden product bag of FIG. 1;

FIG. 6 is a top plan view of the flexible bulk garden product bag of FIG. 1;

FIG. 7 is a bottom plan view of the flexible bulk garden product bag of FIG. 1;

FIG. 8 is a top front left perspective view of the flexible bulk garden product bag of FIG. 1, shown in use in a filled configuration; and,

FIG. 9 is a left side elevational view of the flexible bulk garden product bag of FIG. 1, shown in use in a filled configuration.

The flexible bulk garden product bag is shown with a symbolic break in its length. The appearance of any portion of the article between the break lines forms no part of the claimed design. The broken lines showing of straps is for the purpose of illustrating portions of the flexible bulk garden product bag and do not form any part of the claimed design. Additional broken lines in the figures show environment form no part of the claimed design.
